UNITED STATES PATENT OFFICE.

HENRY WILMOT SPENCER, OF LONDON, ENGLAND.

FEED-WATER REGULATOR FOR STEAM-BOILERS.

1,150,399.

Specification of Letters Patent. Patented Aug. 17, 1915.

Application filed January 5, 1915. Serial No. 685.

To all whom it may concern:

Be it known that I, HENRY WILMOT SPENCER, of 147 Queen Victoria street, in the city of London, England, have invented certain new and useful Improvements in Feed-Water Regulators for Steam-Boilers, of which the following is a specification.

This invention relates to apparatus for automatically controlling the supply of feed-water to a steam generator, or similar receptacle, of the type wherein the boiler water and steam act alternately on a chamber containing a vaporizable liquid the pressure from which is transmitted to a chamber where it operates a diaphragm or other suitable device for governing the supply of feed-water.

In such devices as heretofore constructed it has been usual to provide an expansion or vacuum chamber in communication with the chamber containing the vaporizable liquid and to provide means for accelerating or retarding the vaporization of the liquid.

In feed-water regulating apparatus of the general type to which this invention relates it is necessary that the feed valve shall open or close quickly in accordance with the needs of the boiler; the pressure generated in the regulator must therefore always work through the same range and with the same rapidity irrespectively of (1) the boiler pressure or, (2) the atmospheric conditions under which the apparatus is working. These two variable conditions seriously affect the working of the apparatus. In the first place the temperature of the steam under the heat transferring partition forming the bottom of the vaporizable liquid chamber may be that of steam at 50 lbs. pressure or that of steam at 250 lbs. pressure; and secondly the rate of heat loss from the outer surface of the apparatus varies directly as the difference in temperature between that of the liquid inside the vessel and the surrounding atmosphere which latter may in one case be 40° F. and in another case 120° F. The first mentioned of these variable conditions has been met by providing an adjustable extension piece in the liquid chamber above the heat transferring partition by means of which the depth of the layer of liquid on the partition can be varied to suit the temperature of the steam which will enter beneath. To meet the secondly mentioned variable condition it has been proposed to restrict or control the return

flow of the liquid to the partition to replace that driven off by ebullition and evaporation, but the means hitherto adopted for effecting this restriction or control have not been either convenient or sufficiently satisfactory.

Continued experiments on the general lines above indicated have led to the discovery that an expansion or vacuum chamber which has hitherto been considered essential is not necessary for the satisfactory working of apparatus of this kind, and that better results can be obtained without it.

According to the present invention a continuous conduit or circulating coil is fixed to the upper part of the liquid chamber and is arranged in such a manner that both ends are more or less directly over the heat transferring partition in the vaporizable liquid chamber. The conduit is provided with a screw valve adjustable externally for the purpose of restricting or increasing the return flow of the liquid to the vaporizable liquid chamber. A much greater cooling or radiating surface is provided by this arrangement than by an expansion chamber and by means of the adjustable screw valve the rate of heat loss can be compensated for with great facility.

My invention is illustrated in the accompanying drawings wherein:

Figure 1 is a partly sectional elevation of the apparatus; and Fig. 2 is an elevation showing it applied to a steam boiler.

The same parts are lettered to correspond in both figures of the drawings.

In these drawings A represents the boiler, B and B' are, respectively, steam and water connections from the boiler to the space C' under the heat transferring partition C² of the vaporizable liquid chamber C.

D is the stem of the regulator which is secured in the upper end of the liquid chamber C and is externally threaded at its lower end d being provided with a screw ferrule d' which is adjusted nearer to or farther away from the partition C² of the liquid chamber C as desired. Through the stem D is a central passage D' opening communication between the interior of the chamber C and a cavity D² in the upper part of said stem. Two other passages D³ and D⁴ open into the cavity D², the former being of equal bore with that of the central passage D' and having secured therein the inlet end of the circulating coil E, while the latter is constricted and adapted to be closed by the

conical valve F screwing through a threaded aperture in the outer part of the stem.

G is a cap to protect the screw valve F from dirt and dust.

5 The constricted passage D⁴ opens into a full bore passage in a branch D⁵ connected to the expandible chamber of the diaphragm valve H, into which branch leads another full bore passage D⁶ into which the outlet 70
10 end of the circulating coil is secured. The upper part of the coil is provided with a plugged aperture J for the introduction of water or other liquid.

It is obvious that the circulation from the 15 partition C² through the continuous conduit E and back to the partition can be entirely stopped by closing up the constricted aperture D⁴ by means of the conical screw valve F, consequently it is possible to control the 20 rate of the circulation of the liquid through the apparatus by the adjustment of the valve F so as to cause the pressure to work uniformly over the desired range irrespectively of the rate of heat loss. It should be borne 25 in mind that the range of pressure through which an apparatus of this kind works is required to be usually much lower than the boiler pressure.

The operation of the apparatus is as follows:—On heat being supplied beneath the 30 heat transferring partition C², the temperature of the liquid on its upper surface is raised and ebullition causes some of the liquid to be driven up into the continuous conduit E and this displaces an amount of liquid therethrough which passes back to the partition past the restricting screw valve F. In this way a circulation is set up which quickly raises the temperature of the liquid 35 throughout the continuous conduit, following this steam is generated on the partition and collects in the upper part of the liquid chamber around the outside of the adjustable extension piece d'. If the liquid 40 returns to the partition c² at too low a temperature it retards the generation of pressure and if it returns too hot it accelerates the generation of pressure. Both of these 45 effects are serious as they prevent the proper opening and closing of the feed valve. It is however quite easy so to adjust the restricting screw valve F that the rate of the 50 return flow to the partition will be just that necessary to maintain the liquid at a suitable temperature in the continuous conduit and to cause the pressure to rise and fall uniformly and with the required speed to operate the feed valve H. Should the heat 55 loss from the surface of the continuous conduit be great owing to the apparatus being fixed in a comparatively cold place, the return flow would be increased by screwing the valve F back out of the constricted way D⁴ so that a rapid circulation is allowed 60 throughout the system and in this way the 65

temperature of the liquid could be maintained at that necessary for the working pressure of the apparatus. On the other hand if the apparatus were fixed in a hot place so that the heat lost by radiation 70 would be small, then a considerable restriction of the return flow would be necessary and this would be found to prevent the temperature of the liquid rising too high and the same working pressure could be maintained. 75

The provision of a continuous conduit and the filling aperture at the upper part thereof entirely obviates the precautions and processes heretofore necessary to free the 80 system from air; because as the liquid is poured into that part of the conduit opposite the filling aperture J, the liquid displaces the air in the system and forces it out through the other member of the conduit 85 leaving the system sufficiently free from air.

What I claim is:—

1. In a feed-water regulator, the combination with the boiler of a chamber for containing volatile liquid, a heat transferring partition forming the bottom of said chamber, a second chamber underneath of said partition, means for connecting said second chamber with the water and steam spaces of the boiler, a continuous conduit both ends 90 of which are in open communication with the upper part of said chamber, adjustable means for regulating the depth of the layer of liquid in the liquid chamber and adjustable means for regulating the rate of return 95 flow of the liquid from the continuous conduit to the said chamber and an adjustable feed water valve connected to said conduit, substantially as described.

2. In a feed-water regulator, the combination with the boiler of a chamber for containing volatile liquid, a heat transferring partition forming the bottom of said chamber, a second chamber underneath of said partition, means for connecting said second chamber with the water and steam spaces of the boiler, a stem secured in the upper part of said chamber and having a passage therethrough, an adjustable extension piece on the lower part of said stem, a continuous 105 conduit with both ends connected to said stem and adjustable means for regulating the rate of return flow of the liquid from the continuous conduit to the said chamber and an adjustable feed water valve connected to said conduit, substantially as described. 110

3. In a feed-water regulator, the combination with the boiler of a chamber for containing volatile liquid, a heat transferring partition forming the bottom of said chamber, a second chamber underneath of said partition, means for connecting said second chamber with the water and steam spaces of the boiler, a stem secured in the upper part 115 of said chamber and having a passage there- 120

through, an adjustable extension piece on the lower part of said stem, a continuous conduit with its outlet limb connected to said stem and its return limb connected with a branch pipe, a constricted outlet to said branch pipe opening into the stem passageway, and a conical valve screwing through the stem to seat on said constricted outlet and an adjustable feed water valve connected to said conduit, substantially as described.

4. In a feed-water regulator, the combination with the boiler of a chamber for containing volatile liquid, a heat transferring partition forming the bottom of said chamber, a second chamber underneath of said partition, means for connecting said second chamber with the water and steam spaces of

the boiler, a stem secured in the upper part of said chamber and having a passage therethrough, an adjustable extension piece on the lower part of said stem, a continuous conduit with its outlet limb connected to said stem and its return limb connected with a branch pipe opening into the stem passageway, a conical valve screwing through the stem to seat on said constricted outlet, and a filling aperture in the upper part of said conduit and an adjustable feed water valve connected to said conduit, substantially as described.
